UNITED STATES PATENT OFFICE

2,511,963

COMBINED STRUCTURE FOR CONTROLLING
A RADIO RECEIVING SET AND A CLOCK

Mae Brener, Newton, Mass.

Application June 13, 1946, Serial No. 676,548

8 Claims. (Cl. 250—14)

1

My present invention relates to novel combinations of a radio receiving set and a clock or other device by which the radio receiving set is concealed and its control operating means, while readily available, are so disposed that they do not detract from the appearance of the clock or its case.

Clocks, barometers, thermometers, and the like are, at all times, available for inspection and to that extent they are utilitarian even though their cases are largely ornamental. Radio receiving sets, on the other hand, are not constantly in use and although many radio receiving set cases or cabinets have a degree of utility, as furniture, they are often difficult to locate to the advantage of a room.

In conventional radio receiving sets, there are usually three controls and often more. One of these is the main switch and commonly its operation also permits tone modification. Another control is used to vary the volume. The third control is used in the selection of the stations and requires a substantial range of operation to provide accuracy of tuning or station selection. In addition to the third control, "push button" station selectors are commonly employed and some radio receiving sets are provided with clock controlled circuits which may be pre-set so that the desired station may be automatically tuned in at the desired time. These supplement the third control and are capable of being incorporated in any structure without being objectionably noticeable. The third control, however, is very difficult to make less conspicuous and at the same time retain ease and accuracy in its use.

In accordance with my invention, I mount a radio receiving set behind a device of which a clock is a good example, in supporting structure, the front of which has a dial for the device and which has at least one set of indicia arranged preferably arcuately with respect to the center of the dial. A radio receiving set has at least one rotatable control operator and I provide control operating means including a rotatable element substantially in axial alignment with the dial center and an arm extending through the front and formed for use with reference to the indicia.

While the dial of the device may have the indicia marked on it and the device may have a hollow shaft through which the control operating arm extends, I prefer that the front be formed with a slot substantially arcuate with respect to the center of the dial and disposed adjacent its periphery. This preferred construction may be most conveniently effected by providing the supporting structure for the radio receiving set and

2

the device with a member having an aperture to accommodate the device and to provide a seat to which the dial may be attached.

As one of the advantages of my invention is that it makes possible a unit that may be mounted in a clock case, a housing, a recess in a wall, furniture, or in any structure where either such a device as a clock or a radio receiving set may be desired, it is desirable to provide structure that combines attractiveness of appearance, utility, and convenience of assembly or of service.

In its preferred form, accordingly, I provide the front member with an inset surface having an aperture thereby to establish a seat to which the dial may be secured and to accommodate the device itself. The member has at least one recess in communication with the aperture and arcuate with respect to the center thereof. When the dial is attached to its seat, a portion of that recess is exposed as a slot for the control operating arm. If a crystal supporting bezel is used, it is conventionally attached to the member to cover the dial and the recess is dimensioned so that a portion of it is exposed as an arcuate slot for the arm.

By this construction, the device may be easily removed and replaced. At the same time, when the radio receiving set has cross sectional measurements less than those of the opening through the member, it enables easy assembly and service of the radio receiving set.

In the accompanying drawings, I have shown illustrative embodiments of my invention from which these and other of its novel features and advantages will be readily apparent.

In the drawings:

Fig. 1 is a front view of a clock and radio receiving set combined and mounted in accordance with my invention in a clock case of conventional design.

Fig. 2 is a fragmentary and partly sectioned view showing the supporting structure by which the radio receiving set and the clock are mounted in the case.

Fig. 3 shows the radio receiving set mounted in the case as viewed from the rear with the housing broken away to show the control opening means.

Fig. 4 is a front view of the face member of the supporting structure.

Fig. 5 is a fragmentary side view of the radio receiving set with its housing broken away to show the control operating means, and

Fig. 6 is a view generally similar to Fig. 2, but showing another embodiment of my invention.

In the embodiment of my invention shown in

Figs. 1-5, I have indicated generally at 10 supporting structure for use in mounting the clock 11 and the radio receiving set 12 in the chamber 13 in the clock case 14. The clock case may be of conventional design and is illustrative of other structures in which, in accordance with my invention, a radio receiving set may be mounted behind a device of which a clock is the best example.

The clock 11 may be of any type and has a dial or face 15, hands 16 and 17. For convenience, I have indicated at 18 electric driving mechanism having a lead 19.

The radio receiving set 12 may also be of any desired type, but is preferably of small size and for that reason I have not detailed its construction. I have indicated at 20 its housing and its power lead at 21. The radio receiving set 12 is shown as having rotatable control operators indicated generally at 23, 24, and 25. The control operator 23 may, for example, control the main switch and tone modification. The control operator 24 is used to vary the volume and the operator 25 controls the selection of the stations. The loud speaker or speakers, not shown, may be separately supported where desired in the chamber 13 or such may be built into the unit indicated generally at 12. The radio receiving set 12 may include static arrestors and if it be a battery operated set, the batteries may also be housed in the case 14.

While the supporting structure may be otherwise made, I have shown in the drawings the supporting structure 10 as comprising a base 26 seated in the chamber 13 in the aperture in the case 14 and on the shoulder 27 in its back wall 28. The base 26 has a socket 29 for the plugs 30 and 31 in the leads 19 and 21 respectively. The base 26 has a platform 32 having a slotted upright 33 which the flanged rear end 34 of the housing 20 enters as a locking lip. At its other end, the housing 20 is anchored to the platform 32 as by the screw 35.

The supporting structure 10 also includes a face or front member 36 adapted to be attached to the case 14 as by screws 37. The face member 36 has inset flanges 38 establishing a seat to which the clock face 15 may be secured as by screws 39 and defining an aperture 40 to accommodate the clock mechanism 18. Preferably, as shown in the drawings, the radio receiving set 12 is dimensioned so that it may be inserted into or removed from the chamber 13 through the aperture 40. Where my invention is embodied in a clock case or portable structure, it may, of course, be removed through the back thereof, if desired, and where the radio receiving set 10 is of such size that it cannot be removed through the aperture 40, it must, of course, be removed from the back.

At 41, 42, and 43 I have indicated recesses in communication with the aperture 40. As may be most clearly seen in Fig. 4, these recesses are arcuate with reference to the center of the aperture 40 and extend radially outwardly a sufficient distance so that when the clock face 15 is seated, portions of the recesses are exposed as marginal slots. Where the clock face 15 is to be covered by a crystal 44, the bezel 45 is conventionally mounted as by a hinge in the seat to expose the arcuate slots. The face member 36, the bezel 45, or both, may be provided with suitable indicia adjacent the arcuate slots as suggested in Fig. 1. Where illumination of the clock face is desired, the bezel 45 may be made of transparent or translucent stock in order that

the same light source may also illuminate such indicia.

In the drawings, see Figs. 3 and 5, I have shown the control operator 25 as axially aligned with the center of the clock face 15 and as consisting of shaft 46. Fast on the shaft 46 is an arm 47 extending radially outwardly through a slot 48a in the housing 20 for the radio receiving set 12. Outside the housing 20, the arm 47 extends forwardly through the slot established by the recess 43 and the bezel 45 where it terminates in a pointer 48 disposed to traverse the indicia on the bezel.

The control operators 23 and 24 are shown as mounted eccentrically with respect to the center of the clock face 15 and as having pulleys 49 and 50. Pulleys 51 and 52 are mounted on the shaft 46 for rotation independently thereof and are connected as by bands 53 and 54 to the pulleys 49 and 50 respectively. Fast on the pulley 51 is an arm 55 extending radially outwardly through the slot 56 in the housing 20 and extending forwardly through the arcuate slot defined by the recess 42 and the bezel 45. I also secure to the pulley 52 an arm 57 which extends radially outwardly through the slots 58 in the housing 20 and extends forwardly through the arcuate slot defined by the recess 41 and the bezel 45. The arms 55 and 57 terminate in inwardly disposed pointers 59 and 60 respectively. For convenience in assembly or service, I have shown the rear end of the housing 20 as open.

By this construction, I am able to provide an attractive assembly in which one or more of the rotatable control operators has manually operable means that are conveniently available for easy and accurate adjustment but are relatively inconspicuous and do not interfere with the appearance of the case or housing in which the radio receiving set is mounted. When service of the radio receiving set is necessary, it is only necessary to swing the bezel into its open position, remove the clock 11, remove the screw 35 and disconnect the plug 31. The radio receiving set 12 may then be removed through the face member 36 and the clock 11 replaced, if desired.

In Fig. 6, I have shown another embodiment of my invention in which similar supporting structure 61 supports the radio receiving set 62 and the clock 63 in the chamber 13 of the indicated case 14. In this embodiment of my invention, I have shown only the rotatable control operator 64 which may be regarded as the control by which station selection is effected. The control operator 64 extends axially through the clock 63 and through the hollow hub 65 for the hand 66 and on which the hand 67 is mounted for rotation independently thereof. At its exposed end, the operator 64 has a pointer 68 disposed to traverse indicia adjacent the periphery of the clock face 69 on the face member 70 of the supporting structure 61.

From the foregoing, it will be apparent that my invention enables radio receiving sets and other devices, such as clocks, to be attractively combined. While my invention may be variously modified, the embodiments which I have described well illustrate its general features and advantages.

What I therefore claim and desire to secure by Letters Patent is:

1. Structure for use in combining a clock having a dial and a radio receiving set having at least one movable control in a clock case chambered to house said set and having an aperture 75 in its front face in communication with said

chamber and in which said clock is to be mounted, said dial including a face member attached to the front face of said case and having a slot therein adjacent said dial and communicating with said chamber through said aperture, a bezel attached to said dial with a portion closely adjacent and parallel to said slot and control moving means connected to said control and including an arm extending outwardly from said case through said slot disposed to traverse that part of said bezel that is adjacent thereto.

2. The structure of claim 1 in which a support for the set is secured to the face member.

3. Structure for use in combining a clock having a dial of predetermined size and shape and a radio receiving set having at least one movable control in a case chambered to house said set and having an aperture in its front face in communication with said chamber and in which said clock is to be mounted, said structure comprising a member of greater size than said aperture and attached to said case marginally thereof, said member having an aperture and including a portion extending inwardly from its inner edge and constituting a seat to which said clock dial is attached adjacent its periphery to establish a slot adjacent said dial for said control, and a support for said set connected to said member.

4. Structure for use in combining a clock having a dial of predetermined size and shape and a radio receiving set having at least one movable control in a case chambered to house said set and having an aperture in its front face in communication with said chamber, said structure comprising a member of greater size than said aperture and attached to said case marginally thereof, said member having an aperture and including at least one portion extending inwardly from its inner edge and constituting a seat to which said clock dial is attached adjacent its periphery, the remainder of said inner edge being of the shape of said clock face but dimensioned so that said inner edge and the periphery of said clock face define a slot, and control moving means connected to said control and including an arm extending outwardly from said case through said slot.

5. The structure of claim 4 in which a bezel of the size and shape of the dial is connected thereto and has indicia thereon with reference to which the arm is readable.

6. Structure for use in combining a clock having a dial of predetermined size and shape and a radio receiving set having at least one movable control in a case chambered to house said set and having an aperture in its front face in communication with said chamber, said structure

comprising a ring, the outside diameter of which is greater than that of said aperture and which is connected to said front face, said ring including at least one projection on its inner edge engageable with the clock dial adjacent its periphery when seated thereagainst and to which said dial is attached, the inner edge of said ring, except for said projection, being of substantially the same shape as the adjacent portions of the periphery of said dial but having a diameter sufficiently greater than the maximum dimension of said dial to define therewith a slot intermediate adjacent projections, and control moving means connected to said control and including an arm extending from said chamber outwardly through one of said slots.

7. Structure for use in combining a clock having a dial of predetermined size and shape and a radio receiving set having a plurality of movable controls in a case chambered to house said set and having an aperture in its front face in communication with said chamber, said structure comprising a ring the outside diameter of which is greater than that of said aperture and which is connected to said front face, said ring including a plurality of spaced projections on its inner edge engageable by the clock dial adjacent its periphery when seated thereagainst and to which said dial is attached, the inner edge of said ring, except for said projections, being of substantially the same shape as the adjacent portions of the periphery of said dial but having a diameter sufficiently greater than the maximum dimension of said dial to define therewith a slot intermediate adjacent projections, and control moving means for each of said controls, each of said means including an arm extending from said chamber outwardly through one of said slots.

8. The structure of claim 7 in which the projections are disposed to establish a plane countersunk with respect to the exposed face of the ring.

MAE BRENER.
